(57) **CLAIM**

The ornamental design for a upper frame for baby walker, as shown and described.

DESCRIPTION

FIG. 1 is a perspective view of a upper frame for baby walker showing my new design;

FIG. 2 is a front elevational view thereof;

FIG. 3 is a rear elevational view thereof;

FIG. 4 is a left side view thereof;

FIG. 5 is a right side view thereof; and,

FIG. 6 is a top plan view thereof.

The bottom of the upper frame for baby walker forms no part of the claimed design.
